[57] ABSTRACT

A new and distinct cultivar of Chrysanthemum plant named 'Cream Reagan', bearing small to medium sized pale yellow blooms with a yellow-green center and performance of 24–28 days.

2 Drawing Sheets

1

The cultivar 'Cream Reagan' as described and illustrated herein is related to the following cultivars:

'Dark Red Reagan' (U.S. Plant Pat. No. 9,929);
 'Sunny Reagan' (U.S. Plant Pat. No. 9,928);
 'Reagan' (U.S. Plant Pat. No. 8,642);
 'Salmon Reagan' (U.S. Plant Pat. No. 8,869);
 'Sulfur Reagan' (U.S. Plant Pat. No. 8,786);
 'Dark Reagan' (U.S. Plant Pat. No. 8,966);
 'Orange Reagan' (U.S. Plant Pat. No. 8,769);
 'Bronze Reagan' (U.S. Plant Pat. No. 8,865);
 'White Reagan' (U.S. Plant Pat. No. 8,784);
 'Coral Reagan' (U.S. Plant Pat. No. 8,974);
 'Yellow Reagan' (U.S. Plant Pat. No. 8,884);
 'Dark Splendid Reagan' (U.S. Plant patent application Ser. No. 08/646,224); and
 'Splendid Reagan' (U.S. Plant patent application Ser. No. 08/738,605).

BACKGROUND OF THE INVENTION

The present invention comprises a new and distinct cultivar of Chrysanthemum plant which is a natural occurring sport of a parent Chrysanthemum named 'Reagan'. Parent Chrysanthemum 'Reagan' is described in U.S. Plant Pat. No. 8,642. The new cultivar was discovered as a whole plant mutation in 1990 in a greenhouse in Holland.

The invention has been asexually reproduced by cuttings at the same location. The new cultivar has been found to retain all of its distinctive characteristics through successive asexual propagations.

SUMMARY OF THE INVENTION

The present invention is a new and distinct variety of Chrysanthemum of a small to medium sized bloom and pale yellow color.

BRIEF DESCRIPTION OF THE DRAWINGS

The present invention of a new and distinct variety of Chrysanthemum is shown in the accompanying drawings, the color being as nearly true as possible with color photographs of this type.

FIG. 1 shows the full bloom of the new cultivar.

FIG. 2 shows the various stages of bloom of the new cultivar.

FIG. 3 shows foliage and petiole of the new cultivar.

2

DESCRIPTION OF THE INVENTION

This new variety of Chrysanthemum is of the botanical classification *Chrysanthemum morifolium*. When grown in the vicinity of Ter Aar, Holland, it has a response time of approximately 7½ weeks. This new variety produces small to medium sized pale yellow blooms with a yellow-green center having a 4 week performance (i.e., vase life of 24–28 days). This new variety of Chrysanthemum has been found to retain its distinctive characteristics throughout successive propagations and may be planted under greenhouse conditions in Holland between weeks 50 and 35.

The following is a description of the plant and characteristics (color designations are from R.H.S. Color Chart) that distinguish it from related known varieties and its antecedents. The color designations are taken from the plant itself. Accordingly, any discrepancies between the color designations and the colors depicted in the photographs are due to photographic tolerances.

Detailed Botanical Description and Comparative Data		
CULTIVAR	Cream Reagan	Sunny Reagan
<u>Bud</u>		
Size	Medium cross section ±1.0 cm	Medium cross section ±1.0 cm
30 Form	Round and flat	Round and flat
Outside Color	Near Yellow 8A	Between Yellow 7A/Yellow 9A
<u>Bloom</u>		
Size	Small to Medium 6–6½ cm	Medium 6½–7 cm
35 Fully Expanded	Upper portion single flower per peduncle lower portion plural flowers per peduncle	Upper portion, single flower per peduncle, lower portion plural flowers per peduncle
Form	Near Yellow 8A	Between Yellow 7A/Yellow 9A
<u>Peduncle Lengths</u>		
40	Near the top ±14 cm, near the middle ±24 cm near the bottom ±28 cm	Near the top ±14 cm, near the middle ±24 cm, near the bottom ±28 cm medium
Peduncle Lateral Shoot, Attachment	Medium	medium
Peduncle Lateral Shoot, Angle		
Form	Single (Daisy)	Single (Daisy)
Performance	Very good 24–28 days (18–20° C.)	Very good 24–28 days (18–20° C.)
